ABSTRACT: A vending machine of the type having side hinged, drop-shelf dispensing assemblies is provided with shelf releasing mechanisms and control structure, including a common, vertically reciprocable actuating bar, which permits a double-depth arrangement of a number of side-by-side pairs of shelf columns. The releasing mechanisms permit the use of a single bar between the front and rear stack of shelves of each pair and operable such that the force which effects release of the mechanisms is in the same direction as gravity. The shelves are released consecutively from the bottom to the top of one stack and thence from the bottom to the top of the other stack. Switching apparatus permits initial setting for vending to commence either at the bottom of the front stack or the bottom of the rear stack.

DOUBLE-DEPTH DROP-SHELF DISPENSING MECHANISM

It is an important object of the present invention to provide a vending machine having maximum space conserving characteristics, by doubling the number of shelves without increasing the width of the front of the machine, through use of front and rear drop shelf columns, together with novel shelf releasing mechanisms permitting use of a common actuating bar that requires very little space and utilizes force of gravity in its operation.

Another very important object of the instant invention is to provide a vending machine of the aforementioned character which permits, each time the machine is serviced, setting of the cycle of operation by the service man in a manner to cause initial vending of old merchandise, so that, for the most part, the fresh new products replenished by the serviceman are the last to be vended.

Other features of my present invention include novel shelf releasing mechanisms and control structure making the above objects possible, all to be made clear as the following specification progresses, reference being had to the accompanying drawings, wherein:

FIG. 1 is a side elevational view of one unit having a pair of double-depth drop-shelf dispensing mechanisms for vending machines made pursuant to my present invention;

FIG. 2 is a top plan view of the unit of FIG. 1;

FIG. 3 is an enlarged cross-sectional view taken on line 3-3 of FIG. 1;

FIG. 4 is a view similar to FIG. 3 except for different positions of the releasable mechanism of the upper shelf of the front stack and the holding means for the releasable mechanism of the lower shelf of the rear stack;

FIG. 5 is a cross-sectional view taken on line 5-5 of FIG. 3;

FIG. 6 is a cross-sectional view taken on line 6-6 of FIG. 5;

FIG. 7 is a fragmentary top plan view showing a portion of the support for the unit of FIG. 1 and associated sold-out arrangement;

FIG. 8 is a cross-sectional view taken on line 8-8 of FIG. 7;

FIG. 9 is an enlarged, fragmentary, elevational view of a portion of the unit showing that side thereof opposite to FIG. 1 with parts broken away and in section for clearness;

FIG. 10 is a fragmentary front elevational view of the unit shown in FIG. 1;

FIGS. 11 and 12 are cross-sectional views taken on lines 11-11 and 12-12 respectively of FIG. 9 but rotated 180°;

FIG. 13 is a detailed view similar to FIG. 1 showing a different position of one of the releasable mechanisms; and

FIGS. 14-17 are schematic views showing various positions of the releasable mechanisms.

Unit 20 includes a front and a rear U-shaped support 22 and 24 respectively having their bights 26, 28 joined by upper track 30 and lower track 32. Flanges 34 and 36 of support 22 receive hinge pins 38 for a stack of vertically spaced, front, article-retaining shelves 40, and flanges 42 and 44 of support 24 receive hinge pins 46 for a stack of vertically spaced, rear, article-retaining shelves 48. When the shelves are horizontal (FIG. 10) they are in their article-holding condition; when vertical (FIG. 10) they are in their article discharge condition. Opposed extensions 50 from flanges 36 and 44 are joined by crossbars 52.

Since the releasable mechanisms between flanges 36 and 44 for each of the shelves 40 and 48 respectively are identical, one only, in connection with one of the front shelves 40, will be described. It includes a part or element 54 rigidly secured to shelf 40 for swinging movement therewith and a part 56, carried by support 22, in the nature of a releasable spring latch on flange 36 that is shiftable against its inherent resiliency.

Element 54 is mounted on pin 38 and further secured to shelf 40 by a hook 58 which passes through arcuate slot 60 in flange 36 and through the proximal hinge pin receiving flange 62 depending from shelf 40. A latch-engaging ear 64 rigid to element 54 swings downwardly with shelf 40 when latch 56 is released.

Wire latch 56 has a V-shaped portion 66, the apex of which is retained in slot 68 at the corner between flange 36 and extension 50. The free end of portion 66 is hooked into a projection 70 struck from flange 36. The upper leg of portion 66 is shiftable in a slot (FIGS. 11 and 12) formed in a projection 72 struck from flange 36, such upper leg terminating in an L-shaped portion 74 that is offset from flange 36 and normally engages ear 64 therebeneath. Thus, an upwardly inclined force on portion 66 with respect to projection 72, releases ear 64 for gravitational movement of shelf 40 to its vertical position.

Each element 54 has a pivot pin 76 rigid thereto and parallel with pin 38 which carries plate 78 of a swingable latch release arm or trigger means 80, plate 78 having a trip-engaging tab 82 and a lock-engaging tang 84, the latter of which is provided with a tongue 86 and a latch-engaging finger 88.

In addition to the ear 64, each element 54 has lock means in the nature of a normally upstanding leg 90 provided with an uppermost edge 92 and a prong 94. Except for the uppermost and the lowermost lock means, each edge 92 normally has the tang 84 next above in engagement therewith. The upper ends of prongs 94 of the two uppermost lock means normally support other components, as hereinafter explained.

During shelf resetting the prong 94 maintains engagement with the tang 84 of the latch release arm or trigger 80 thereabove to prevent the leg 90 of the element 54 from getting on the wrong side of the trigger 80. When a trigger 80 is driven, by means to be described, to effect release of the corresponding shelf, the edge 92 of the element 54 of that shelf drops away from normal supporting relation to the trigger 80 of the shelf thereabove causing that trigger to swing downwardly until the end of finger 88 engages the latch 56 of the latter shelf.

Control structure for the mechanisms above described includes a vertically reciprocable bar 96 between the flanges 36 and 44 normally resting on a stop 98 and held to a rectilinear path of travel by slotted guide 100 adjacent stop 98 as well as by slotted guides 102 and 104 on track 30 and uppermost crossbar 52 respectively. Bar 96, common to the mechanisms of the two stacks of shelves 40 and 48, has trip means for the triggers 80 in the nature of opposed pairs of laterally extending lugs 106 adapted to engage the tabs 82.

The control structure includes also a novel switching apparatus having a pair of shiftable lever devices 108 and 110 swingable about a horizontal shaft 112 carried by the extensions 50, 50 and extending into overlying relationship to the two uppermost prongs 94. Additionally, there is provided a pair of releasable lever members 114 and 116, carried by the lowermost crossbar 52 by hooks 117 for up and down swinging movement, into and out of engagement with the lowermost tangs 84.

Device 108 and member 114 correspond to shelves 40; device 110 and member 116 correspond to shelves 48. Device 108 is coupled with member 116 by a pull rod 118 through coil spring 120 on rod 118 below member 116. A pull rod 122, crossing rod 118, couples device 110 with member 114 through a coil spring 124 on rod 122 below member 114.

An L-shaped projection 126 on the lowermost crossbar 52 holds bar 96 in the guide 100 and supports a switching plate 128 for swinging movement about upright pintle 129. Upstanding handles 130 and 132, which may be marked "front" and "rear" respectively, are integral with plate 128. When handle 130 is turned out, as shown in FIGS. 1 and 3-6, it slides plate 128 beneath a strip 134 on the lowermost crossbar 52 and cams the member 114 downwardly, out of engagement with the tang 84 thereabove, compressing spring 124, by engagement with inclined edge 136 of an upturned piece 138 integral with member 114. Conversely, when handle 132 is turned out (not shown) it slides plate 128 beneath a strip 140 on the lowermost crossbar 52 and cams the member 116 downwardly, out of engagement with the tang 84 thereabove, compressing spring 120, by engagement with inclined edge 142 of an upturned piece 144 integral with the member 116.

Compression of springs 120 and 124, as aforesaid, is caused by the fact that the devices 108 and 110 are being held upwardly, preventing downward movement of rods 118 and 122, by the corresponding uppermost prongs 94 upon which devices 108 and 110 rest when the two uppermost shelves 40 and 48 are horizontal. FIG. 8 shows device 110 held up by the proximal prong 94, and illustrates device 108 lowered.

A leaf spring 146, held rigid on projection 126, has opposed, upturned ends 148 that are received alternately by hole 150 of plate 128 to yieldably maintain plate 128 in either of its two operating positions.

When all of the shelves 40 and 48 have been released, both of the devices 108 and 110 will have dropped, thereby lowering an actuator 152 for a sold-out switch 154 (FIG. 7); upstanding triangles 156 on the devices 108 and 110 normally hold actuator 152 elevated as shown in FIG. 8. Actuator 152 and switch 154 are mounted on a cabinet frame member 158 along which track 30 slides when the unit 20 is pulled out for servicing the shelves 40 and 48, track 32 also having a similar guide (not shown) in the cabinet. Manifestly, a front door of the vending machine cabinet is opened to render all of the side-by-side units accessible.

At the commencement of such servicing, the serviceman must first flip all of the empty shelves to their horizontal position where they are automatically caught by the latches 56, i.e., the ears 64 deflect the portions 74 and slip into place thereabove. This is accomplished by running his fingers along the ends of shelves 40 and 48 remote from flanges 36 and 44 and progressively raising the shelves from bottom to top.

The lowermost shelves 40 and 48, however, of each unit 20 must be raised before the same can be pulled out for resetting the shelves as above described, since associated structure (not shown) would interfere with the movement of the shelves while in the vertical position thereof. The lowermost shelf 48 may be difficult to reach for such purpose; therefore, a handle 160 at the front of unit 20 below shelves 40 may be turned to rotate rod 162 and move a deflector 164 against the lowermost shelf 48 to raise the latter from its vertical position until it becomes latched in place.

OPERATION

With reference to but one of the units 20 of the machine, and assuming that all of the shelves 40 and 48 are horizontal and filled with merchandise, such as candy bars, the switching plate 128 must be in one of its two positions; otherwise, both members 114 and 116 would remain lowered and no shelf 40 or 48 would be released by reciprocation of bar 96. If handle 130 faces outwardly, as shown in FIGS. 1 and 3-6, and locked in place by one end 148 of leaf 146 being in hole 150, plate 128 will depress piece 138, and therefore, the member 114. Spring 124 permits depression of member 114 while device 110 is held up by the proximal uppermost prong 94 (FIG. 3); rod 118 maintains member 116 in the up position. (Member 114 is omitted from FIGS. 3 and 4 for clearness.)

Therefore, all of the tabs 82 are held out of the path of travel of the lugs 106 of bar 96 except the tab 82 corresponding to the lowermost shelf 40 which is held out of the path of travel of the proximal lug 106 by member 116. All remaining tabs 82 are held in such inoperative position by the lock means next below, i.e., the edges 92 of the legs 90 receiving the tangs 84 of the triggers 80, for example, as shown in FIGS. 3 and 14.

Thus, when bar 96 is initially raised away from stop 98, that lowermost lug 106 thereof corresponding to the lowermost shelf 40 will engage the lowermost face of the proximal tab 82 raising the latter and swinging its trigger 80 in a direction which moves finger 88 away from latch 56 (FIG. 16). Before bar 96 reaches the upper end of its stroke, tab 82 will slip off the lug 106 and trigger 80 will swing freely back by gravity until finger 88 engages portion 74 of latch 56, returning tab 82 into the path of descent of lug 106. As bar 96 gravitates and lug 106 engages the upper face of tab 82, trigger 80 will be caused to swing on its pivot pin 76 to force finger 88 against

latch portion 74. This shifts portion 74 from beneath the ear 64 of the element 54 of the lowermost shelf 40 (FIG. 17), permitting the latter to gravitate to a vertical position (FIG. 10) dumping its product for movement to a position accessible to the customer.

Spring latch 56 snaps back to the position in which it is yieldably biased and when shelf 40 is later raised past its horizontal position, ear 64 deflects latch portion 74 to pass the latter. Then, when the shelf is released, ear 64 comes to rest on such portion 74 thereabove, holding the shelf substantially horizontal.

Movement of the lowermost shelf 40 to its article discharge condition also swings the leg 90, thereby withdrawing edge 92 from beneath the tang 84 of the trigger 80 next above, i.e., the trigger 80 corresponding to the second from the bottom shelf 40. Such released trigger 80 is then hanging freely on its pin 76 and its tab 82 is in readiness for actuation by the second cycle of reciprocation of bar 96.

Thus on successive actuations of the bar 96, all of the shelves 40 are released progressively, and as the uppermost shelf 40 discharges its product, its prong 94 will move from the position shown in FIG. 3 to the lowered position shown in FIGS. 4 and 8, dropping the device 108. As rod 118 descends, the member 116 will drop from the position shown in FIGS. 3, 5 and 6 to the position shown in FIG. 4. Member 116 thereby releases the trigger 80 of the lowermost shelf 48 so that the shelves 48 are thereafter released from bottom to top in successive order. When the uppermost shelf 48 releases its device 110, both triangles 156 will have been retracted, lowering actuator 152 to operate sold-out switch 154.

The serviceman then opens the front door of the vending machine cabinet, raises the lowermost shelves 40 and 48 by turning handle 160, and pulls the unit 20 outwardly to a position rendering the remaining shelves 40 and 48 accessible for flipping upwardly in successive order from bottom to top to their horizontal positions for refilling with products.

Before closing the cabinet, the serviceman will set the switching plate 128 so that vending commences either from the bottom shelf 40 or the bottom shelf 48, depending on which of the columns of shelves 40 or 48 had products remaining at the time of servicing. If, for example, he replenished all of the shelves 40 with fresh products, and only certain of the lower shelves 48 with fresh products, it would be desirable to discharge the remaining old products on the upper shelves 48 before vending from shelves 40. He accomplishes this result merely by turning plate 128 to dispose the handle 132 outwardly. This lowers the member 116, and the member 114 remains in the up position, held by device 110, rod 122 and spring 124. After shelves 48 are all emptied, vending switches automatically to the shelves 40 as is obvious from the above descriptions.

Coin control mechanisms, power means for raising the bar 96 and other conventional apparatus commonly employed in automatic vending machines form no part of the present invention and have, therefore, not been included herein. Suffice to point out that the novel features of the instant invention and the arrangement of all its components permit the use of any of a number of different types of necessary or desirable assemblies and parts without need for special, complicated or expensive developments.

We claim:

1. In a vending machine:
  - a first and a second series of vertically spaced article retainers, each mounted for movement from an article-holding condition to an article discharge condition; releasable mechanism for each retainer respectively normally maintaining the latter in its article-holding condition; structure operably associated with and common to said mechanisms for releasing the same consecutively from one end of said first series to the opposite end thereof and thence from one end of said second series to the opposite end thereof;

said structure including a single, reciprocable actuator operable to release one mechanism during each cycle of reciprocation of the actuator; and
 said actuator releasing all of the mechanisms of the first series of retainers during a first number of consecutive cycles of reciprocation of the actuator, and thereupon releasing all of the mechanisms of the second series of retainers during a second number of consecutive cycles of reciprocation of the actuator.

2. The invention of claim 1, said structure having switching apparatus for rendering the actuator operable to release said mechanisms consecutively from said one end of said second series to said opposite end thereof and thence from said one end of said first series to said opposite end thereof.

3. In a vending machine:

- a first and a second series of vertically spaced article retainers, each mounted for movement from an article-holding condition to an article discharge condition;
- releasable mechanism for each retainer respectively normally maintaining the latter in its article-holding condition;
- structure operably associated with and common to said mechanisms for releasing the same consecutively from one end of said first series to the opposite end thereof and thence from one end of said second series to the opposite end thereof;
- said structure including control means adapted for actuation in one direction and gravitation in the opposite direction each time a retainer is to be released; and
- each mechanism having releasing means operable upon one gravitation of said control means.

4. In a vending machine:

- a first and a second series of vertically spaced article retainers, each mounted for movement from an article-holding condition to an article discharge condition;
- releasable mechanism for each retainer respectively normally maintaining the latter in its article-holding condition;
- structure operably associated with and common to said mechanisms for releasing the same consecutively from one end of said first series to the opposite end thereof and thence from one end of said second series to the opposite end thereof;
- said structure including a releasable member normally inactivating the mechanism for the retainer next adjacent said one end of the second series; and
- a device operably coupled with said member and responsive to movement of the retainer next adjacent said opposite end of the first series to its article discharge condition for releasing said member.

5. In a vending machine:

- a first and a second stack of vertically spaced article retainers, each mounted for movement from an article-holding condition to an article discharge condition;
- releasable mechanism for each retainer respectively normally maintaining the latter in its article-holding condition;
- structure operably associated with said mechanisms for either releasing the same consecutively from the bottom to the top of the first stack and thence from the bottom to the top of the second stack or alternately, from the bottom to the top of the second stack and thence from the bottom to the top of the first stack;
- said structure including a releasable member for each stack respectively;
- each member being movable from a released position to a position inactivating the mechanism for the lowermost retainer of its respective stack;
- means responsive to movement of the uppermost retainer of the first stack to its article discharge position for moving said member of the second stack to its released position;
- means responsive to movement of the uppermost retainer of the second stack to its article discharge condition for

moving said member of the first stack to its released position; and

switching apparatus for alternately holding either of said members in its released position.

6. In a vending machine:

- a first and a second stack of vertically spaced article retainers, each mounted for movement from an article-holding condition to an article discharge condition;
- releasable mechanism for each retainer respectively normally maintaining the latter in its article-holding condition;
- structure operably associated with said mechanisms for either releasing the same consecutively from the bottom to the top of the first stack and thence from the bottom to the top of the second stack or alternately, from the bottom to the top of the second stack and thence from the bottom to the top of the first stack;
- said structure including:
- a first releasable member movable from a released position to a position inactivating the mechanism for the lowermost retainer of the first stack;
- a second releasable member movable from a released position to a position inactivating the mechanism for the lowermost retainer of the second stack;
- a first shiftable device responsive to movement of the uppermost retainer of the first stack to its article discharge condition;
- a second shiftable device responsive to movement of the uppermost retainer of the second stack to its article discharge condition;
- means coupling the first device with the second member for moving the latter to its released position when the uppermost retainer of the first stack moves to its article discharge condition;
- means coupling the second device with the first member for moving the latter to its released position when the uppermost retainer of the second stack moves to its article discharge condition; and
- switching apparatus for alternately holding either of said members in its released position.

7. In a vending machine:

- a front and a rear stack of vertically spaced, article-receiving shelves, each mounted for movement from an article-holding condition to an article discharge condition;
- releasable mechanism between the stacks for each shelf respectively normally maintaining the latter in its article-holding condition;
- a vertically reciprocable bar between the stacks and common thereto for releasing one mechanism of one of the stacks each time the bar is raised and lowered;
- each mechanism having a releasable latch normally holding its shelf in said article-holding condition and a latch releasing trigger movable to and from a position engageable by said bar;
- each shelf except the uppermost shelf of each stack having means releasing the trigger next above for movement to said position engageable by said bar as the shelves move to their article discharge condition;
- means responsive to movement of the uppermost shelf of the front stack to its article discharge condition for releasing the trigger of the lowermost shelf of the rear stack;
- means responsive to movement of the uppermost shelf of the rear stack to its article discharge condition for releasing the trigger of the lowermost shelf of the front stack; and
- means for holding either of the triggers of the lowermost shelves against movement to said position engageable by the bar.

8. In a vending machine:

- a front and a rear stack of vertically spaced, article-receiving shelves, each mounted for movement from an article-holding condition to an article discharge condition;

releasable mechanism between the stacks for each shelf respectively normally maintaining the latter in its article-holding condition; a vertically reciprocable bar between the stacks and common thereto for releasing said mechanisms consecutively until all shelves of both stacks have moved to their article discharge conditions; each mechanism having a trigger for releasing the same, said bar having a series of trigger trips reciprocable therewith; and there being a trip for each trigger respectively, each trigger being movable to a position for actuation by its corresponding trip upon movement of the shelf therebelow to its article discharge condition.

9. In a vending machine: a front and a rear stack of vertically spaced, article receiving shelves, each mounted for movement from an article-holding condition to an article discharge condition; releasable mechanism between the stacks for each shelf respectively normally maintaining the latter in its article-holding condition; a vertically reciprocable bar between the stacks and common thereto for releasing said mechanisms consecutively until all shelves of both stacks have moved to their article discharge conditions; releasable holding means precluding operation of the mechanisms of one of the stacks by the bar until all of the shelves of the other stack have moved to their article discharge conditions; and means responsive to movement of all of the shelves of said other stack to their article discharge conditions for releasing said holding means.

10. In a vending machine: a support; an article retainer mounted on the support for movement from an article-holding condition to an article discharge condition; releasable mechanism having normally interengaging parts on the support and on the retainer respectively for maintaining the latter in its article-holding condition; trigger means movable to and from a mechanism releasing position; control means adapted for actuation in one direction and for gravitation in the opposite direction; and said control means having trip means for moving the trigger means to said position during gravitation of the control means.

11. The invention of claim 10, said trigger means being disposed for movement by the trip means away from said mechanism when the control means is actuated, and toward said mechanism during gravitation of the control means.

12. The invention of claim 10, said part on the retainer being rigid thereto for movement therewith; said trigger means being carried by said part on the retainer for movement therewith and free movement relative thereto.

13. The invention of claim 10, said part on the support comprising a shiftable latch; said trigger means having a latch engaging finger for shifting the latch to a position out of engagement with said part on the retainer during gravitation of the control means.

14. The invention of claim 10, said trigger means having tab means engageable by said trip means; said tab means being disposed to be raised by the trip means when the control means is actuated and to be lowered by the trip means during gravitation of the control means.

15. In a vending machine:

a support; an article shelf swingable on the support for movement from an article-holding condition to an article discharge condition; an element rigidly secured to said shelf for swinging movement therewith; a releasable spring latch mounted on the support and normally engaging said element to hold the shelf in its article-holding condition; a trigger carried by said element for swinging movement therewith and free swinging movement relative thereto; a vertically reciprocable control bar having a laterally extending trip; a tab on said trigger engageable by said trip, said tab being disposed to be moved by the trip to swing the trigger in one direction relative to said element when the bar is raised and to be moved by the trip to swing the trigger in the opposite direction relative to said element during descent of the bar; and a latch engaging finger on said trigger, said finger being disposed to move away from the latch when the trigger swings in said one direction relative to said element and into engagement with the latch to release the latter when the trigger swings in said opposite direction relative to said element.

16. In a vending machine: a support; a stack of vertically spaced article retainers, each mounted on the support for movement from an article-holding condition to an article discharge condition; releasable mechanism for each retainer respectively having normally interengaging parts on the support and on the retainer respectively for maintaining the latter in its article-holding condition; movable trigger means for each mechanism respectively, and shiftable control means common to said retainers having trip means for each trigger means respectively; each trigger means having a first position out of the path of travel of its corresponding trip means, a second position within said path of travel of its said corresponding trip means, and a third position releasing its corresponding structure; each retainer, except the uppermost of said retainers, having releasable lock means normally maintaining the trigger means of the retainer next above in said first position; each lock means being released by movement of its corresponding retainer to the article discharge condition; each trigger means moving freely to said second position upon release of the lock means next below; and each trip means engaging the corresponding trigger means, when the latter is in said second position, and moving the same to said third position upon actuation of said control means.

17. The invention of claim 16, said control means comprising a vertically reciprocable bar: each trip means comprising a lateral extension on the bar, each trigger means having a tab disposed to be moved aside by the corresponding extension, when the bar is raised, to a fourth position of the trigger means where the tab clears the extension; and each trigger means returning freely to said second position when its tab is cleared by the corresponding extension for reengagement of the tab by its extension when the bar descends.
